UNITED STATES PATENT OFFICE.

KARL EHRCOTT, OF ERIE, PENNSYLVANIA, ASSIGNOR TO BERNARD GLOEKLER COMPANY, OF PITTSBURGH, PENNSYLVANIA, A CORPORATION OF PENNSYLVANIA.

ELECTRIC BROILER STRUCTURE.

Application filed September 12, 1925. Serial No. 56,047.

The object which I have in view is the provision of an electric broiler structure which will be inexpensive of construction, durable, easy to repair, and in which the electric heating elements may be quickly and conveniently removed or replaced by an unskilled person, and without the use of special tools.

For this purpose I have invented the new and improved broiler structure hereinafter described.

In the accompanying drawings, wherein I illustrate the best embodiment of the principles of my invention now known to me, Fig. 1 is a plan view of the broiler grill with the electric heating elements mounted therein; Fig. 2 is an end view of the same, also showing it supported in position for use, and Figs. 3, 4 and 5 are sectional details taken along the lines III—III; IV—IV and V—V, respectively.

Referring in detail to the drawings, 1 represents the electric heating elements, which are shown as of a well known commercial type and whose end portions are reduced in thickness, as shown at 2 forming a shoulder 3 a short distance from each end.

4 represents a pair of spaced apart angle bars positioned in parallelism with their vertical flanges inwardly and cut away at regular intervals, thus providing the gaps 5 separated by the vertical tongues 6.

7 represents a pair of bars which connect the ends of the bars 4 together and hold said bars rigidly in proper relation to each other.

The bars 7 rest on top of the ends of the bars 4 and are bolted or riveted thereto, as shown at 8. The bars 7 are preferably angle-bars with their vertical flanges turned inwardly, and the vertical flanges of both the bars 4 and 7 are cut away at their intersections as shown in Fig. 1.

45 When the heating elements 1 are mounted in position, their end portions extend through the gaps 5 and rest on the top of the horizontal flanges of the bars 4.

The heating elements 1 are held in position by means of the bars 9 which are superimposed on the bars 4. The bars 9 are also preferably angle-bars with their vertical flanges turned outwardly and their outer edges substantially flush with the outer edges of the bars 4, and they are sup-

ported in place, so as not to bind the ends of the heating elements, by means of spacing blocks 10 secured, as by spot welding, on the bars 4 in alinement with the tongues 6, the ends of the heating elements being 60 between the blocks 10.

One of the bars 9 is removably secured in place as by the bolts 11 extending down through the said bars and through the blocks 10 and bars 4. The other bar 9 may 65 be permanently riveted in place, as shown in Fig. 4.

The horizontal flanges of the bars 9 are sufficiently narrow to allow sufficient space between their inner edges and the shoulders 70 3 of the heating elements 1 to permit the free expansion of the latter without contact.

12 represents the connecting posts of the heating elements, which posts are positioned sufficiently distant from the end supports 75 of the elements as to avoid possibility of contact. 13 represents the cross connection between the posts, and 14 the conductors by means of which the current is led in.

In case it is desired to remove or replace 80 one or more of the electric heating elements, one of the bars 9 may be quickly removed, the heating element or elements lifted out and new ones substituted and the bar 9 returned to its position and bolted 85 in place.

It is evident that my improved broiler structure is of simple and inexpensive construction, yet is efficient and durable.

The griddle may be supported in position 90 in any convenient manner. Thus in Fig. 2 I have shown the horizontal supports 15 upon which the sides of the griddle rest.

What I desire to claim is:—

1. In an electric broiler, the combination 95 with a plurality of parallel electrical heating elements, of a pair of supporting bars disposed at right angles to the heating elements and of angle cross-sectional shape with their horizontal flanges disposed outwardly and their vertical flanges disposed upwardly, the vertical flanges of said supporting bars being cut away at spaced intervals to form gaps through which the ends 100 of the heating elements extend, the ends of said heating elements being supported in position by resting upon the horizontal flanges of said supporting bars, and bars secured to the supporting bars and spaced 105 above the horizontal flanges of the latter 110

and crossing over the ends of said heating elements to prevent material vertical movement of the heating elements relative to the supporting bars.

- 5 2. In an electric broiler, the combination with the heating elements of a pair of parallel supporting bars of angle cross-sectional shape with their horizontal flanges disposed outwardly and their vertical flanges disposed upwardly and longitudinal bars connecting together the corresponding ends of the supporting bars, the vertical flanges of the supporting bars being cut away at spaced intervals to form gaps through
- 10

which the ends of the heating elements extend, said heating elements being supported in place by their ends resting on the horizontal flanges of the supporting bars, and other bars secured to the supporting bars and spaced above the horizontal flanges of the same and crossing over the ends of the heating elements to prevent material vertical movement of the heating elements relative to the supporting bars.

Signed at Pittsburgh, Pa., this 3rd day of September, 1925.

KARL EHRGOTT.
